UNITED STATES PATENT OFFICE.

ARTHUR C. LOUTHAN, OF ARCOLA, ILLINOIS.

RAILROAD-GATE.

1,297,197.

Specification of Letters Patent. Patented Mar. 11, 1919.

Application filed March 15, 1918. Serial No. 222,786.

To all whom it may concern:

Be it known that I, ARTHUR C. LOUTHAN, a citizen of the United States, residing at Arcola, in the county of Douglas and State 5 of Illinois, have invented certain new and useful Improvements in Railroad-Gates, of which the following is a specification.

This invention relates to an improved railroad gate and the principal object of the 10 invention is to provide improved actuating means for lowering the gate, the actuating means being so constructed that it may be operated from the train the train supplying the power for rotating a drum to wind a 15 cable thereon lowering the gate.

Another object of the invention is to so construct this structure that a release may be operated from the train to release the gate and permit it to rise.

20 Another object of the invention is to so construct this device that the gate may be lowered by a train approaching from either direction thus permitting its use on a single as well as a double track road.

25 Another object of the invention is to provide an operating mechanism for a railroad gate which mechanism will be comparatively simple in construction and comprise a comparatively few parts, all of which will be 30 strong and durable and not liable to easily get out of order.

This invention is illustrated in the accompanying drawings, wherein:

Figure 1 is a top plan view showing the 35 improved structure in operative relation to a railroad gate and track.

Fig. 2 is a side elevation of the structure shown in Fig. 1.

Fig. 3 is a transverse sectional view taken 40 along the line 3—3 of Fig. 1, with the gate in a raised position.

Fig. 4 is a vertical sectional view taken along the line 4—4 of Fig. 1.

Fig. 5 is a fragmentary view taken longitudinally of the track and showing a portion 45 of the gate operating mechanism in side elevation, and

Fig. 6 is a perspective view of the trigger forming part of the releasing mechanism.

50 Fig. 7 is a detail section taken on the line 7—7 of Fig. 1.

The actuating mechanism for the railroad gate 10 will be positioned to extend along the track and will be mounted upon the ties 55 11 between the rails 12 and will further extend beneath the crossing platform 13 posi-

tioned at the roadway. This gate is of a conventional construction and will be pivotally connected with the standard 14 through the medium of the shaft or axle 15 60 upon which will be mounted the drum 16 having the springs 17 connected therewith as shown in Figs. 3 and 4. These springs 17 engage a pulley 18 and are connected with lines or cables 19 which pass about pulleys 65 20 and extend through the standard or housing and are led to the large pulleys 21 mounted between the upper and lower bars 22, the ends of which are secured to the supporting bars 23 positioned between certain 70 of the ties 11. These cables 19 engage pulley wheels 24 and are led along the track in opposite directions and wound upon the drums 25 rotatably mounted between the bearing brackets 26. These drums will be 75 mounted a sufficient distance from the crossing to permit the gate to be closed or lowered before a train reaches the road. Each drum 25 is provided with an enlarged band or turning roller 27 which is mounted rotatably thereon and carries a rubber tire 28. This end of the drum is provided with a ratchet 27' as shown in Fig. 7 of the drawing and the band 27 carries pawls 28' adapted to engage the teeth of this ratchet so that 80 as the tire is frictionally engaged by the shoe 39 carried by the pilot of the engine when the engine is moving forwardly, a rotary movement will be imparted to the drum. When the engine is moving rearwardly, 90 however, the pawls will ride over the teeth in the ratchet and consequently permit the roller 27 to rotate in the reverse direction without imparting movement to the drum. The opposite end of the drum is provided 95 with a ratchet 29 engaged by a pawl 30 pivotally connected with one of the bearing brackets 26 as shown in Fig. 5 and engaged by a link 31 connected with the lever 32. This lever 32 is engaged by a spring 33 and 100 the pawl 30 will thus be yieldably held in the position shown in Fig. 5 to engage the ratchet wheel and hold the drum against rotation in one direction. A line 34 leads from the lever 32 along the track and is 105 connected with the arm 35 of the rocker shaft or trigger 36, the rocker shaft being provided with a second arm 37 extending upwardly and terminating in a roller 38 at its free end. It will be readily seen that 110 when the trigger is moved to draw upon the line 34, the latch or pawl 30 will be moved

out of engagement with the ratchet wheel 29 and the drums thus released permitting the cables 19 to be unwound from the drums.

When in use, this gate operating mechanism will be installed as shown clearly in Fig. 1, and a train approaching the crossing will pass over one of the drums 25. The shoe, 39 mounted upon the pilot of the engine will engage the tire of the band 27 and will rotate the drum thus drawing upon the line 19 to stretch the spring 17 with which the line is connected and thus swing the gate downwardly to its closed or lower position. The pawl through engagement 10 with the ratchet wheel 29 will hold the gate against moving upwardly. If desired a spring element 40 may be provided with the length of the cable between the pulley 24 and the drum, thus preventing danger of the 15 cable being broken under the force of the strain received when the drum is first rotated. After the train has passed the crossing, the shoe 39 will strike the lever arm 37 of the latch or trigger 36 thus rotating the 20 same to swing the arm 35 and draw upon the line 34 and release the latch 30 thus releasing the drum. The gate is weighted as 25 is usual in gates of this character, and therefore when the drum is released the gate will 30 of itself swing to a raised position and the mechanism will be returned to the normal position with the gate swung upwardly as indicated by dotted lines in Fig. 2. As soon as the shoe moves out of engagement with the 35 lever arm 37, the spring 33 will return the pawl 30 into engagement with the ratchet wheel 29 and the operating mechanism is again ready for use. In the present illustration, this mechanism has been shown in connection with a single track railroad and so 40 arranged that it may be operated by a train approaching the crossing from either direction. It will be readily obvious that if installing in connection with a road of double 45 track construction, it will only be necessary to provide for closing the gate when a train approaches along a specified track in one direction. Therefore, it would only be necessary to provide one cable 19, one drum and 50 one trigger 36 and connecting line for the trigger with the latch of the drum for each track. This duplicate structure specified could be applied to the second track so that 55 the gate could be closed by a train approaching on either side.

The shoe 39, carried by the pilot of the engine is attached to a pair of levers 41 pivoted at 42 to the pilot of the engine. The upper ends of the levers 41 are connected by 60 a rod 43 which may be extended in any pre-

ferred manner to the cab of the engine whereby the engineer may actuate the rod 43 to swing the levers 41 on their pivots 42 for the purpose of elevating the shoe 39 whereby it may be in a position to prevent engagement with the winding mechanism when desired. 65

I have therefore provided a railroad gate and actuating mechanism so constructed that the actuating mechanism may be mounted 70 upon the track and operated from the train, the train supplying the power to rotate the drum and wind the cable to lower the gate and further the train providing the means for moving the latch to release the drum and 75 gate and permit the counterweights on the latter to move it to a raised position. It is thus unnecessary to provide driving power other than the train itself. 80

I claim:

1. In a railway gate structure, the combination with the normally open gate, a winding drum mounted between the rails at a point on the track remote from the gate, a cable connecting the drum and gate for closing the latter when the drum is turned, pawl-and-ratchet mechanism for holding the drum against retrograde movement, a trip located near the gate, and connections between it and said pawl; of a band rotatably mounted on the drum and having a rubber tire adapted to be struck by a shoe on an approaching car, and pawl-and-ratchet mechanism between the band and drum whereby movement of the former toward the 95 trip will turn the drum, as described. 90

2. In a railway gate structure, the combination with the normally open gate, a winding drum mounted between the rails at a point on the track remote from the gate, a cable connecting the drum and gate for closing the latter when the drum is turned, pawl-and-ratchet mechanism for holding the drum against retrograde movement, a trip located near the gate, and connections between it and said pawl; of a band rotatably mounted on the drum and having a rubber tire adapted to be struck by a shoe on an approaching car, and connections between the band and drum whereby turning of the former toward the trip will turn the drum but turning of the band in a reverse direction is permitted without turning the drum. 105 110

In testimony whereof I affix my signature in presence of two witnesses.

ARTHUR C. LOUTHAN.
